UNITED STATES PATENT OFFICE.

DAVID V. BUCK, OF NEW COLUMBIA, PENNSYLVANIA, ASSIGNOR OF ONE-HALF TO
JAMES S. REITMEYER, OF NEW COLUMBIA, PENNSYLVANIA.

RAILROAD-TIE.

1,097,070.

Specification of Letters Patent. Patented May 19, 1914.

Application filed February 9, 1914. Serial No. 817,535.

To all whom it may concern:

Be it known that I, DAVID V. BUCK, a citizen of the United States, residing at New Columbia, county of Union, and State of Pennsylvania, have invented certain new and useful Improvements in Railroad-Ties, of which the following is a specification.

My invention relates to railroad ties and particularly to metallic ties.

10 The object of my invention is to provide an improved metallic tie equipped with means for securely holding the rails in position thereon.

A further object of my invention is to 15 provide a tie of the class mentioned of such construction as to permit of the same being quickly arranged in place on the roadbed and is readily removed therefrom without disturbing the superimposed rails or the adjacent ties.

20 A further object of my invention is to provide an improved metallic tie which will be of light weight, simple of construction and equipped with means to prevent slipping 25 of the same from proper position after having been properly placed in the roadbed.

25 A further object of my invention is to provide a metallic railway tie equipped with rail securing means of such construction that 30 the rails may be readily secured thereto at the proper gage without the use of the usual or special instruments.

35 A further object of my invention is to provide a metallic tie with improved rail securing means of such construction as to make accidental unfastening of the same practically impossible and at the same time of such simple construction that the rail may be readily and quickly disconnected 40 from the tie when it is desired to remove either the rail or the tie.

Other objects will appear hereinafter.

With these objects in view my invention consists generally in a railway tie comprising a flat plate of sufficient length and breadth provided on its longitudinal edges with depending flanges and further equipped, intermediate its ends, with a transversely arranged depending flange, 50 which flanges are adapted to be embedded in the ballast of the roadbed to prevent slipping of the tie.

My invention further consists in a tie comprising a flat metal plate provided with

depending longitudinal flanges further characterized by equipping the same with permanent rail securing members rigidly secured thereto and adapted to engage the respective rails upon the same or corresponding sides and removable fastening devices adapted to engage the respective rails upon the opposite sides, whereby when said removable fastening devices are displaced the tie may be moved by longitudinal movement from beneath the rails without disturbing the same or the adjacent ties.

My invention further consists in the improved rail fastening or securing devices and in various details of construction and arrangements of parts all as will be fully described hereinafter and particularly pointed out in the claims.

My invention will be more readily understood by reference to the accompanying drawings forming a part of this specification and in which—

Figure 1 is a top plan view of a tie including the rail securing means, embodying my invention in its preferred form, and illustrating sections of the rails secured in position, Fig. 2 is a plan view of the tie with the rails and removable fastening devices removed therefrom, Fig. 3 is a vertical longitudinal section of the tie, rails, and fastening devices taken upon the line 3—3 of Fig. 1, Fig. 4 is an end elevation of the same, Fig. 5 is an enlarged detail transverse sectional view through one of the rails, and the upper plate or body of the tie, and illustrating the rail securing devices in elevation, Figs. 6 and 7 are detail perspective views upon an enlarged scale of the members of the removable fastening devices, Fig. 8 is a rear elevation of the modified form of one of the members of the fastening devices, 95 and Fig. 9 is a side elevation of the same.

Referring now to the drawings 1 indicates the tie which comprises a flat metallic plate 2 of sufficient length and breadth to properly support upon the roadbed the superimposed weights to which it is subjected, and formed on its longitudinal edges with depending flanges 3. Intermediate the ends of the tie I provide a depending transversely positioned flange 4 which, when embedded in the ballast of the roadbed, prevents creeping or slipping of the tie thereon. The flange 4 may be secured to the tie in

any preferred manner. As shown in the drawings it comprises a section of angle bar riveted to the body or plate 2.

Fixed to the upper face of the tie 1 are the permanent rail securing members 5 which are arranged apart a distance equal to the gage at which it is desired to lay the rails. These members each comprise a base 5' by which it is secured to the tie as by rivets 6 and an inclined portion or tongue 5" which engages over the flange of the rail. The two members 5 are similarly positioned upon the tie so as to engage the two rails upon the same or corresponding sides, so that, when the removable fastening devices, described hereinafter, are displaced, the tie may be readily moved longitudinally of the same from beneath the rails without disturbing the latter or the adjacent ties.

Adjacent the members 5 and spaced from the base 5' thereof a distance substantially the width of the flange of the rails, the body 2 of the tie is provided with apertures 7 to receive the removable rail securing devices. These devices comprise generally a gib 8, and a key 9 and a cotter pin 10. The gib comprises a body or shank 11 and a tongue or flange 12 adapted to engage over the flange of the rail when the shank is positioned within the aperture 7. The shank 11 is of a width to fit snugly within the aperture 7 and is provided at its lower end with laterally offset portions or lugs 13 which engage under the plate 2 adjacent the aperture and with a third lug 14 adapted to engage under the portion of the plate 2 beneath the rail flange as shown clearly in Fig. 5. To facilitate inserting the gib within the aperture 7 the portion of said aperture farthest removed from the rail is enlarged transversely as at 7' to permit the lugs 13 to pass readily therethrough. After the lugs pass through the portion 7' of the aperture the gib is removed into the narrower portion of the aperture adjacent the rail thereby positioning the lugs 13 and 14 beneath the adjacent portions of the plate 2 as above mentioned. The under face of the tongue or flange 12 is upwardly inclined to conform to the usual taper or inclination of the rail flange and the distance between the under face of said tongue and the upper faces of the lugs 13 and 14 is so proportioned as to wedge the flange and adjacent portion of the tie body between them, and in order to prevent the gib from reaching the end of the aperture 7 before securely clamping the rail to the tie said aperture is arranged to extend a slight distance beneath the flange as clearly illustrated in Fig. 5. The body or shank 11 of the gib is preferably slightly tapered with the thicker portion at the lower end for a purpose which will appear hereinafter.

The key comprises a body or shank 15,

adapted to fit snugly within the wider portion 7' of the aperture and a laterally offset head 16. The body 15 is provided with a medial vertically disposed rib 17 of a width substantially equal to the narrower portion of the aperture 7 and tapered reversely or complementary to the taper of the body of the gib so that by driving the key into the aperture, the portion 17 engages the outer face of the gib and forces the same toward the rail to clamp the latter to the tie. The outer face of the gib is provided with a horizontal or transverse groove 18 and the adjacent face of the key, with a plurality of corresponding grooves 19. When the key is driven sufficiently to cause the gib to properly clamp the rail, and one of the grooves 19 is brought into registry with the groove 18, the cotter pin 10 is inserted through the opening formed thereby and securely locks the members against accidental displacement particularly if the ends 10' of the cotter pin are turned in the usual manner. The head 16 affords an extended surface to receive the blows of the instrument for driving the key and also affords means for engaging a crow bar or the like thereunder for removing the key.

If preferred, the gib including the tongue 12 may be made the full width of the key or of the portion 7' of the aperture and the lateral edges thereof notched as indicated at 20 in Fig. 7 to receive the portion of the plate adjacent the aperture 7 and to form the lugs 13 which engage thereunder, or the entire gib with the exception of the lugs 13 may be formed of a width equal to that of the aperture 7 as shown in Figs. 8 and 9.

The tongue 5" of the fixed locking members and the tongue 12 of the removable locking members extend well up upon the opposite flanges of the rail or adjacent the web so as to more securely hold the rail in position. The manner of assembling the parts and disjoining the same will be clear from the foregoing description.

I claim:

1. A tie comprising a hollow body portion and provided with an upper surface adapted to support traction rails, similarly disposed clamps secured upon said tie adjacent the opposite ends thereof and adapted to engage over one of the base flanges of each of the traction rails, said upper surface being provided with openings adjacent the opposite base flange and extending partly thereunder, said openings being widened at their outer ends to form key ways, gibs of substantially the same width as the widened ends of said openings and provided at their medial portions with notches to permit of their sliding therein said narrower portions of the opening, the rear walls of said gibs being inclined inwardly in an upward direction and provided adjacent their upper ends

with transverse grooves, lugs adjacent the bottom upon the forward faces of said gibs for engagement with the under surface of said tie, keys adapted to slide within said key ways and provided upon their rear portions with outwardly extending inclined faces, the said inclined faces being provided with a plurality of transverse grooves, and pins adapted to be inserted within the openings formed when the grooves of said gibs and keys are in register, substantially as described.

2. A hollow tie provided adjacent the opposite ends of its upper surface with similarly disposed clamps adapted to engage over the inner and outer base flanges of the opposite rails respectively of a railroad track, angular slots provided in said upper surface extending partly under and beyond the outer edges of the opposite base flanges of said rails, said slots being widened at their outer extremities to form key ways, gibs provided adjacent their lower ends with oppositely disposed lugs adapted to be admitted to said narrower portions of the slots through said key ways, lugs upon the forward vertical faces of said gibs adjacent the lower ends thereof for engagement with the under face of said upper surface when in position, the rear vertical wall of said gibs being inclined inwardly in an upward direction and provided with transverse grooves adjacent their upper end, keys adapted to be inserted within said key ways and provided with their rear faces with outwardly extending portions provided with downwardly inclined faces adapted to engage the adjacent faces of said gibs, each of said keys provided with a series of transverse grooves, and cotter pins adapted to be inserted within

in the openings formed when the grooves of said gibbs and keys are in register, substantially as described.

3. A hollow tie provided adjacent the opposite ends of its upper surface with similarly disposed clamps adapted to engage over the inner and outer base flanges respectively of the opposite rails of a railroad track, angular slots provided in said upper surface extending partly under and beyond the edges of the opposite base flanges of said rails, said slots being widened at their outer extremities to form key ways, gibs provided at their upper ends with inwardly extending portions adapted to engage over the said opposite base flanges and with grooves in their sides to permit of their sliding within the narrow portions of said slots, lugs upon the forward faces of said gibs adjacent the lower ends thereof for engagement with the under surface of said tie and the opposite vertical face of said gibs being inclined inwardly in an upward direction, keys provided at their upper ends with heads adapted to be inserted within said key ways and provided upon their rear faces with outwardly extending downwardly inclined portions adapted to engage the inclined rear faces of said gibs when in position, transverse grooves in the adjacent inclined faces of said gibs and keys, and pins adapted to be inserted within the opening formed when said grooves are in register, substantially as described.

In testimony whereof I have signed my name to this specification in the presence of two subscribing witnesses. 75
